UNITED STATES PATENT OFFICE.

ABRAHAM ROSENBERG, OF FAR ROCKAWAY, NEW YORK.

METHOD OF PRODUCING APPAREL ORNAMENTS.

Application filed August 28, 1925. Serial No. 53,188.

My invention relates to the production on garments of ornaments such as frogs, edging, or the like. The invention has particularly in view the production, directly in situ on the garment, of frogs or like looped ornaments, although the invention is not limited in all its phases to the direct production of the ornaments on the garment.

My present invention has for an object 10 to provide an effective means to produce the ornaments in situ on wearing apparel.

A further important object of the invention is to provide for the making of frogs and like ornaments having a plurality of loops formed from a continuous strip and which may be produced without crossing of the corded braid or the like strip employed. The usual way of forming a frog, for example, from corded braid, is to loop the 20 fabric, then pull the cord of the braid in a way to flatten out the loop and remove the puckered or buckled condition which necessarily results from bending the braid into a loop. The steps of looping the braid and 25 then pulling are usually done by holding the braid with the fingers. Moreover, with many forms of ornaments, the usual practice results in having the cord appear in some places of the design at the inner side 30 or bend of a loop and again at the outer side or bend of a loop so that the pulling of the cord does not result in flattening the ornament but leaves the same irregular. It is an important object of my invention to 35 eliminate the objections referred to and provide for the ready flattening out of the ornament by the pulling of the cord of the braid.

My invention also has in view to provide 40 a method for producing looped ornaments wherein the material of the braid forming the loops may be crossed and still the cord be pulled to flatten the loops.

My invention furthermore has for an object 45 to provide an ornament and the method of making the same wherein loops form part of a continuous strip.

The manner and means whereby the above and other objects are attained will clearly 50 appear as the description proceeds.

Reference is to be had to the accompany-

ing drawings forming a part of this specification, it being understood that the drawings are merely illustrative of examples of the invention.

55

Figure 1 is a plan view of a piece of apparel having thereon a frog formed in accordance with my present invention; the view shows the frog before flattening;

Figure 2 is a view similar to Figure 1 60 but showing the ornament after the cord has been pulled to flatten out the loops;

Figure 3 is a plan view of the ornament on the fabric showing the ornament in its completed condition with an embroidered button 65 incorporated therein covering the terminal ends of the strip from which the ornaments are formed and holding the several loops of the ornament in fixed relation;

Figure 4 shows reverse side of the apparel 70 and ornament;

Figure 5 is an edge view of the ornament and piece of apparel;

Figure 6 is a plan view similar to Figure 1 but showing another mode of forming loops 75 with the corded braid crossing at one point;

Figure 7 is a view similar to Figure 6 but showing a further mode of forming the looped ornament involving the crossing of the braid twice;

80

Figure 8 is a view similar to Figures 6 and 7 but showing a further mode of forming an ornament by crossing the braid.

Referring at first more particularly to Figures 1 to 5, in order to produce an 85 ornament of apparel, a fragment of which is indicated at 10, by employing a strip 11 of corded braid as the material for forming the ornament, said braid is disposed on the fabric of the apparel and formed continuously into a series of loops or other figures according to the design of the ornament. As the loops are formed the braid is stitched 90 adjacent the outer edge thereof by a line of stitching 12, which, it will be noted, is at the opposite edge from the cord 14 in the tunneled seam 13.

The ornament in accordance with the present invention is formed from a continuous strip of braid and it is to be noted 100 that the braid in the example shown in Figures 1 to 5, does not cross itself at any

point. On the contrary, the braid at the convergent end of a loop has the inner side edges adjacent. The forming of the braid into a loop gives the braid a gathered or buckled form and the braid must be flattened out, the gathering being due to the fact that the total effective length of the braid at the inner edge is less than the total effective length at the outer edge when the braid is not gathered or buckled. In order to flatten out the braid, the cord 14 is pulled. The cord is free to be pulled throughout the full series of loops, being loose in the tunneled seam 13 and not being held by stitching 12. The cord may be pulled with facility to the extent of straightening out two adjacent loops near each terminal. Figure 1 shows the braid after being sewed and Figure 2 the same braid after being flattened and after the pulling of the cord 14. After the exposed ends of the cord 14 have been cut prior to or subsequent to the forming of a button hole A in one of the loops, where the button hole is to be employed, the adjacent convergent portion of all the loops are covered and held by forming an embroidery button 15 extending through the fabric as will be seen by comparing the views of the reverse sides in Figures 3 and 4 and the edge view in Figure 5. It is to be noted that the terminals of the looped strip of braid lie in substantially the plane of the loops so that the whole ornament is practically in a single plane to lie flat and to be held in the flat form by the embroidery button 15.

In the form shown in Figure 6 a strip 111 of corded braid is imposed upon the apparel material 10 and formed into pairs of loops and the loops of a pair being opposed as in the first described ornament. The loops are formed in the following sequence: That loop shown at the top of Figure 6 is first formed, then the oppositely disposed loop to form a pair, then that loop shown at the left of Figure 6 is formed with the braid crossed over itself adjacent to the first loop as clearly shown. The final loop, that at the right of Figure 6 is then formed. The numeral 113 indicates the tunneled seam of the braid containing the cord and 112 the line of stitching. The stitching at the outer edge of the braid is free of the tunneled seam and cord.

In Figure 7 the braid material is twice crossed over itself. Thus, the left-hand loop of Figure 7 is first formed, then the next adjacent loop of the opposite pair, the braid being then crossed over itself and the loop shown at the right formed, the braid being again crossed on itself and that loop at the top of Figure 7 which is the final loop is formed.

In making the ornament of Figure 8, that loop at the left of the figure is first formed

from the corded braid, and then the loop at the right of the figure, whereupon the braid material is crossed over itself to form that loop shown at the top of Figure 8 and the braid then crossed over itself to form the 70 loop at the bottom of Figure 8. In Figures 7 and 8, as in Figure 6, the numeral 111 indicates the strip of corded braid, the numeral 112, the stitching, the same as previously described, and the numeral 113, 75 the tunneled seam.

In the several ornaments of Figures 6, 7 and 8, the stitching 112 is done with weak thread, readily breakable and the cord in the seam 113 when pulled, causes the stitching 112 to break, permitting the loops to be flattened out as previously referred to.

The present invention is distinguished from the invention in my co-pending application for another method of producing apparel ornaments in that the invention in the present case relates to the direct production of the ornaments on apparel fabric, instead of on a destructible fabric, as in the other case. The invention in the present case is distinguished also in that it involves the production of an ornament from a continuous strip. Also, the present invention in one of its phases defines a method whereby a breakable thread may be employed in the 90 production of ornaments involving the crossing of the material from which the ornament is made.

I would state furthermore that while the illustrated examples constitute practical embodiments of my invention, I do not limit myself strictly to the exact details herein illustrated, since, manifestly, the same can be considerably varied without departure from the spirit of the invention as defined 105 in the appended claims.

Having thus described my invention, I claim:

1. In a method of producing a looped ornament for wearing apparel, disposing a strip of corded braid in looped form directly upon the apparel fabric with the corded edge of said strip lying at the interior of the loop, securing the looped strip to said apparel fabric while leaving the corded edge free, and then pulling the cord to contract the interior of the loop to flatten out puck- 110 erings in the strip by the looping thereof. 115

2. In a method of producing looped ornaments for wearing apparel, disposing a strip of corded braid directly upon the apparel fabric, forming a plurality of connected loops running continuously and with the cord of the braid at the interior of the respective loops, securing the loops to said fabric along a line remote from the cord of said braid, then pulling the cord to contract the material of the loops to flatten out the same. 120

3. In a method of producing a looped or- 130

nement for wearing apparel, securing a strip of corded braid in looped form directly upon the apparel fabric on which the ornament is to permanently appear and with the convergent ends of the loop sides juxtaposed, then pulling the cord of the braid to flatten the loop.

4. In a method of producing for wearing

apparel an ornament having loops; forming a strip of corded braid into a plurality of loops running continuously one with another, securing the braid to a fabric at the edge of the braid opposite the cord, and then pulling the cord for flattening the loops.

ABRAHAM ROSENBERG.
